UNITED STATES PATENT OFFICE.

DAVID SINCOCK, OF CLYDE PARK, MONTANA, ASSIGNOR OF ONE-HALF TO
SOL. P. HEREN, GUY D. HUNTER, JOHN H. MARTIN, AND WILLIAM F.
LEE, OF SAME PLACE.

MOWING-MACHINE.

SPECIFICATION forming part of Letters Patent No. 632,375, dated September 5, 1899.

Application filed May 18, 1899. Serial No. 717,351. (No model.)

To all whom it may concern:

Be it known that I, DAVID SINCOCK, a resident of Clyde Park, in the county of Park and State of Montana, have invented certain new and useful Improvements in Mowing-Machines; and I do hereby declare the following to be a full, clear, and exact description of the invention, such as will enable others skilled in the art to which it appertains to make and use the same.

My invention relates to an improvement in mowing-machines, the object of the invention being to provide a mowing-machine with improved cutter-bar-operating means.

15 A further object is to provide improved means on the cutter-bar of a mowing-machine for reciprocating the cutter-bar.

A further object is to so construct the cutter-operating mechanism of a mowing-machine that the cutter-bar and finger-bar can be raised or lowered without affecting the operating mechanism in the slightest.

20 A further object is to so construct a mowing-machine that the cutter-operating mechanism can be readily disconnected from the cutter-bar to permit the easy removal of the latter.

25 A further object is to provide a mowing-machine which will be extremely simple in construction, cheap to manufacture, and most effectual when in operation.

With these objects in view the invention consists in certain novel features of construction and combinations and arrangements of 30 parts, as will be more fully hereinafter described, and pointed out in the claims.

In the accompanying drawings, Figure 1 is a plan view illustrating my improvements. Fig. 2 is a view in section of same, and Figs. 35 3, 4, and 5 are views of details.

40 A represents the frame of my improved mowing-machine, supported by the axle 1, which is carried by the wheels 2, as shown. A tongue 3 is secured to the frame A and is 45 adapted to support any approved driver's seat. (Not shown.)

The frame A is provided with a bracket 4, projecting to one side of the machine and adapted to support a horizontally-disposed 50 shaft 5, mounted in suitable bearings in the

bracket and projecting through one side thereof for a purpose more fully hereinafter explained. A small sprocket-wheel 6 is secured on the shaft 5 in the bracket 4 and is connected with a large sprocket-wheel 7 on the axle 1 by 55 an endless sprocket-chain 8. The end of the shaft 5 which projects through the bracket is connected with an angular sleeve 9 by a universal coupling 10. An angular rod 11 is loosely mounted in the sleeve 9 and is connected with a shaft 12, revolvably mounted in a frame 13 by a universal coupling 14.

The frame 13 comprises parallel longitudinally-disposed strips or plates 15 and transversely-disposed connecting strips or plates 16. The rear ends of the longitudinally-disposed strips 15 project beyond the rear transverse strip 16 and are provided with holes or openings for the reception of a rod or bolt 17, secured in lugs 18 on a shoe 19. The shoe 19 70 is provided at points between its ends with lugs 20, to which are pivotally secured a loosely-mounted frame 21. The front member 22 of the frame 21 connects the front lug 20 on the shoe with a lug or projection 23 75 on the bracket 4, and a coupling-yoke 24 connects the member 22 with the main portion of the frame, which latter is pivotally connected to downwardly-projecting lugs 25 on the frame A, as shown. The frames A and 80 21 and bracket 4 are held out of contact with the ground (when the tongue 3 is raised) by means of a strip or brace 26, secured at its ends, respectively, to the tongue and frame A. A finger-bar 27, having a series of split 85 fingers 28 on its front edge, is secured to the shoe 19 and provided at its outer end with any approved track-clearer 29.

My improved cutter-bar 30 is mounted on the finger-bar 27 and held against rearward movement by means of lugs or projections 31, secured at points throughout the length of the finger-bar and adapted to overlap the cutter-bar when in place. The cutter-bar is provided at its inner end, on its upper face, with 90 enlargements or blocks 32, spaced apart and provided with inclined inner ends to form an approximately V-shaped recess 33. The shoe 19 is made with a groove 34 for the reception 95 of the contracted inner end of the cutter-bar 100

to permit the cutter-bar between the ends of the blocks 32 to lie flush with the upper face of the shoe, and the frame 13 is provided at diametrically opposite points with recesses 5 35 for the free passage of the blocks 32.

A wheel 36 is mounted in the frame 13 and secured on the shaft 12 and provided around its periphery with a cam-flange or web 37, comprising a series of diagonally-disposed 10 sections connected together at their ends to form a cam-flange on the periphery of the wheel. This flange or web 37 is disposed in the recess 33 between the blocks 32 and as the wheel revolves engages first one block 32 15 and then the other, thus carrying the cutter-bar from one extreme to the other and reciprocating the same.

The frame 13 is provided on its forward transverse strip with parallel lugs 38, between 20 which the forward lug 20 on the shoe 19 is disposed, and a catch 39 is pivotally mounted on the forward lug 20 and adapted to be turned to lock the frame 13 in its downward position on the shoe. Any ordinary lifting-lever (not 25 shown) may be employed for raising and lowering the finger-bar and cutter-bar.

The operation of my improved device is as follows: Motion is transmitted from the sprocket-wheel 7 to the sprocket-wheel 6 by 30 the sprocket-chain 8 to revolve the sleeve 9, rod 11, and shaft 12, carrying the operating-wheel 36, which latter, as heretofore explained, operates to reciprocate the cutter. It will be seen that as my improved operating-wheel 36 35 is mounted directly on the finger-bar, or shoe forming a part thereof, and connected with the operating mechanism by a telescoping flexible shaft, the finger-bar can be raised or lowered without affecting the operating of the 40 device in the slightest, as the telescopic sections of the flexible shaft will take up the shortening of the shaft and revolve the operating-wheel at precisely the same speed to give the cutter-bar its proper throw and al- 45 ways end the throw of the knives in the center of the split fingers.

Various slight changes might be resorted to in the general form and arrangement of the several parts described without departing 50 from the spirit and scope of my invention, and hence I would have it understood that I do not wish to limit myself to the precise details set forth, but consider myself at liberty to make such slight changes and alterations 55 as fairly fall within the spirit and scope of my invention.

Having fully described my invention, what I claim as new, and desire to secure by Letters Patent, is—

1. In a mowing-machine, the combination 60 with a frame, of a finger-bar pivotally connected therewith, a cutter-bar movably mounted on the finger-bar, a frame pivotally connected with the finger-bar and disposed thereon, a wheel revolvably mounted in the frame and a 65 cam-flange on the periphery of said wheel adapted to engage and reciprocate the cutter-bar.

2. In a mowing-machine, the combination 70 with a frame, a finger-bar pivotally connected therewith, and a cutter-bar movably mounted on the finger-bar, of a wheel mounted on the finger-bar, a cam-flange on said wheel adapted to reciprocate the cutter-bar, operating mechanism for the cutter-bar and a flexible 75 telescopic shaft connecting said operating mechanism with the wheel on the finger-bar.

3. In a mowing-machine, the combination 80 with a frame, of a finger-bar pivotally connected with the frame, a shoe secured to the finger-bar, a frame hinged to the shoe, means on the shoe for locking the frame in position, a cutter-bar having one end disposed in said frame, a wheel revolvably mounted in the frame, shoulders on the cutter-bar, a cam-flange on the wheel for engagement with the shoulders on the cutter-bar to reciprocate the latter and a flexible shaft connecting said wheel with the operating mechanism for the 85 mowing-machine.

4. The combination in a mowing-machine 90 of a frame, a shoe hinged thereto, a finger-bar secured to the shoe, a cutter-bar, beveled shoulders on said cutter-bar, a wheel mounted on the hinged shoe over the cutter-bar and 95 provided with a cam-flange operating between said beveled shoulders and means for rotating the wheel.

5. In a mowing-machine, the combination 100 with a frame, of a shoe having a hinged connection in line with its longitudinal axis, with said frame, a finger-bar secured to said shoe, a cutter-bar mounted on the finger-bar and adapted to project across said shoe, beveled shoulders on said cutter-bar, a frame mounted 105 on the shoe and bridging the finger and cutter bars, a cam-wheel mounted in said frame and adapted to engage said beveled shoulders on the cutter-bar to reciprocate the latter and means for rotating said cam-wheel. 110

In testimony whereof I have signed this specification in the presence of two subscribing witnesses.

DAVID SINCOCK.
